UNITED STATES PATENT OFFICE

165,891

AIR COOLER

Daniel D. Wile, Whittier, Calif., assignor to Refrigeration Engineering, Inc., Los Angeles, Calif., a corporation of California

Application November 13, 1950, Serial No. 12,943

Term of patent 14 years

(Cl. D62—4)

To all whom it may concern:

Be it known that I, Daniel D. Wile, a citizen of the United States of America, residing at Whittier, in the county of Los Angeles, and State of California, have invented a new, original, and ornamental Design for an Air Cooler, of which the following is a specification, reference being had to the accompanying drawings, forming a part thereof:

Figure 1 is a perspective view taken slightly below the front of an air cooler embodying my new design;

Figure 2 is a bottom plan view,

Figure 3 is a front elevation,

Figure 4 is a top plan view,

Figure 5 is a side elevation, and

Figure 6 is a rear elevational view thereof.

I claim:

The ornamental design for an air cooler, substantially as shown.

DANIEL D. WILE.
